UNITED STATES PATENT OFFICE.

JAMES R. SUMMERS, OF LOS ANGELES, CALIFORNIA.

ATTACHMENT FOR LATERALLY-SWINGING AWNING ARMS.

Application filed October 25, 1926. Serial No. 143,821.

This invention relates to attachments for laterally swinging awning arms, and is more particularly directed to an attachment adapted to be connected between pivoted arm sections of the laterally swinging arms so as to yieldably urge the same to maintain a tension in the awning.

Awnings as now used to shade display windows and the like are of such construction that the same sag after a short period of use, so that during rain or the like, the same catch and hold a considerable quantity of water which may then be spilled by wind or the like onto pedestrians passing under the awning. The particular awnings concerning which this invention is related are those types of awnings which are rolled up upon a roller when not in use, and after a period of use of these awnings the same roll up so loosely on the rolls as to greatly shorten the life thereof.

It is therefore an object of this invention to provide an attachment for laterally swinging awning arms, that is adapted to be secured between the arm sections of such a collapsible awning arm to yieldably urge the same to the extended position, so as to maintain at all times a tension in the awning.

Other objects and advantages of this invention will be apparent from the following detailed description of a preferred embodiment thereof, as illustrated in the accompanying drawings, in which drawings,

Figure 1 is a fragmental plan view of an awning illustrating the adaptation of an attachment embodying this invention thereto.

Figure 2 is an end section taken on the line 2—2 of Fig. 1.

Figure 3 is a fragmental sectional bottom plan view of an awning attachment embodying this invention.

In the preferred embodiment of this invention illustrated in the accompanying drawings, 1 designates a roll on which the awning cloth 2 is rolled. The roller 1 is secured in position on the face of a building in any desired or preferred manner, as is well understood in the art. Secured to the forward edge of the awning cloth 2 is an awning pole 3, and interposed between the awning pole 3 and the face of the building are laterally swinging awning arms 4.

The awning arms 4 are preferably constructed of a bracket 5 which is rigidly affixed to the face of the building below the roller 1, as illustrated at 6. The brackets 5 are pivotally secured at pins 7 to arms 8. The arms 8

are pivotally secured at their opposite ends at pins 9 to awning pole arms 10. The awning pole arms 10 are pivotally secured at their outer extremities at pins 11 to brackets 12 which are secured to the awning pole 3.

The awning arms 4, as the awning cloth 2 is rolled upon the roll 1, collapses laterally and are so constructed that when the awning cloth 2 is rolled down to the position illustrated in Fig. 1, the same are not at or do not pass center, so that when the roller 1 is actuated, the arms 4 will collapse into the desired position. Interposed between the arms 8 and 10, or between the awning pole 3 and the arm 10, or between the bracket 5 and the arm 8, are spring tension means 13 which are preferably of the following construction:

A disc 14 is formed with a hub 15 at its center, and the pivot pin 9 is passed through the hub 15 and is secured in position by means of a nut 16. Formed on the upper face of the disc 14 is a projecting lug 17 which engages the side of the arm 8. Formed integral with the disc 14 is a circumferential flange 18, providing a cylindrical body within which a coil spring 19 is mounted around the hub 15. One end 20 of the spring 19 is passed through a slot 21 formed in the flange 18, and is thereby secured in position. A cover plate 22 is provided which has formed at its center a hub 23, which has a center bore of sufficient diameter to permit the same to pass over the hub 15 formed in the disc 14. Formed in the hub 23 are a plurality of diametrically opposed slots 25 into any one of which the bent end 26 of the spring 19 may be fitted. Pivotally secured at ears 27 formed integral with the cover plate 22 on a pin 28 is an arm 29 which is formed at its opposite end in an angle section 30.

In adapting this attachment to an awning arm 4, any one of the pivot pins 7, 9 or 11 is first removed and the same is passed through the hub 15 of the disc 14, so that the lug 17 engages either the bracket 5, arm 8 or awning 10, depending upon which one of the pins 7, 9 or 11 is passed through the hub 15. The cover plate 22 is then positioned so that the end 26 of the spring 19 passes through the correct slot 25 formed in the hub 24 of the cover plate 22. The cover plate 22 is then rotated to impart a tension to the spring 19, and the arm 29 is rotated on its pin 28 into position so that the angle section 30 thereof will engage either the arm 8, 10 or the awning pole 3. By means of the plurality of slots

25 formed in the hub 24 of the cover plate 22, an adjustment is provided whereby any desired or predetermined tension may be imparted to the spring 19.

5 With the attachment position as shown in Fig. 2, there is maintained upon the arms 8 and 10 a spring tension which at all times yieldably urges the same toward the extended position so as to maintain a tension in the 10 cloth 2 and prevent the same from sagging. The spring tension maintained by this attachment also takes up any wear or stretch that may occur in the awning cloth 2.

In order to prevent the arms 8 and 10 from 15 swinging to a straight line position or past center, the awning arm 10 is pivotally secured at the pin 9 to the awning arm 8 so that its inner edge 31 engages the face of the hinge plate bracket 32 through which the pin 9 20 is passed.

Having fully described the preferred embodiment of my invention, it is to be understood that I do not wish to be limited to the exact details herein set forth, which may obviously be varied without departing from the 25 spirit of my invention as set forth in the appended claims.

I claim:—

1. In combination with a laterally swinging awning arm, a bracket, an arm pivotally secured to the said bracket, an awning pole, an arm pivotally secured to the awning pole at one end and pivotally secured to the first 30 said arm at the other end, of a disc mounted 35 on the pivot between the said arms and having a lug adapted to engage the first said arm,

spring means mounted on the said disc and secured thereto at one end, a plate mounted on said pivot pin and secured to the said spring at its other end, and an arm secured 40 to the said cover plate and adapted to be engaged with the second said awning arm.

2. In an attachment for laterally swinging awning arms, the combination of a disc having a central hub through which a pivot pin 45 between two arms of the said laterally swinging awning arm passes, a lug formed integral with the said disc and adapted to engage one of said arms, a cover plate, spring tension means interposed between the said cover plate and the said disc, an arm pivotally secured to the said cover plate and having an angle section at its end adapted to engage the other of said awning arms.

3. In an attachment for laterally swinging awning arms having a pair of arms pivotally secured together at their ends, the combination of a disc adapted to be mounted on the pivot connection between said arms and having a projection adapted to engage one of 55 said arms, spring tension means mounted on the said disc and secured at one end thereto, a cover plate, means formed integral with the cover plate for adjustably securing the same to the other end of said spring means, and an arm pivotally secured to the said cover plate and adapted to engage the other of said awning arms.

Signed at Los Angeles, California, this 18 day of October, 1926.

JAMES R. SUMMERS.
